(57) **CLAIM**

The ornamental design for a beverage holder, as shown.

DESCRIPTION

FIG. 1 is a front view of a beverage holder showing my new design.

FIG. 2 is a front, left side perspective view thereof.

FIG. 3 is a top, rear perspective view thereof; and,
FIG. 4 is a top, front perspective view thereof.

The beverage cooler has 2 holes in the product for 2 fingers, one finger in each hole, which allows the product to be carried with one hand. The product could be made from ceramic, plastic, metal or any rigid waterproof material. This product can be painted or decorated.
